(No Model.)

H. C. MARX.
MUSICAL INSTRUMENT.

No. 585.218.

Patented June 29, 1897.

Fig. 1.

UNITED STATES PATENT OFFICE.

HENRY C. MARX, OF CHICAGO, ILLINOIS.

MUSICAL INSTRUMENT.

SPECIFICATION forming part of Letters Patent No. 585,218, dated June 29, 1897.

Application filed December 26, 1896. Serial No. 617,001. (No model.)

To all whom it may concern:

Be it known that I, HENRY C. MARX, a citizen of the United States, residing at Chicago, in the county of Cook and State of Illinois, 5 have invented certain new and useful Improvements in Musical Instruments, of which the following is a specification.

This invention relates to improvements in that class of musical instruments known as 10 "autoharps," in which metallic bars or other hard substance, in combination with strips of felt or similar material, are employed to operate on the strings; and it consists in certain 15 peculiarities of the construction, novel arrangement, and operation of the various parts thereof, as will be hereinafter more fully set forth and specifically claimed.

The main objects of my invention are to provide a musical instrument of the order or 20 class known as "autoharps," which shall possess means for producing clear fret-tones like that of a cithern; to so construct the instrument that a less number of strings are required than is used on the autoharp of the ordinary or general construction, yet attaining 25 the tones produced by the omitted strings and rendering the operation of learning or playing the instrument more easy and simpler; to provide the instrument with dampers, which 30 shall act on each and every bar and key; to enable strings of the same length to be used, and yet to produce uniform and equal vibrations; to enlarge the volume of tone; to produce 35 the chromatic and diatonic scales on every string; to produce the chromatic and diatonic scales in chords; to furnish an instrument that shall produce every key, both major and minor, complete, also dominant seventh, diminished seventh, and dominant 40 to minor in every key.

Other objects and advantages will appear in the description hereinafter set forth.

In order to enable others skilled in the art to which my invention pertains to make and 45 use the same, I will now proceed to describe it, referring to the accompanying drawings, in which—

Figure 1 is a plan view of the instrument, showing a portion of one of the side rails for 50 the fret-bars broken away to show the slots or guideways and springs therefor. Fig. 2 is an enlarged sectional view, partly in eleva-

tion, taken on line 2 2 of Fig. 1, showing a part of the upper portion of the sounding-box and a portion of the dampers and fret-bars in 55 position to act on the strings. Fig. 3 is an enlarged sectional view, partly in elevation, taken on line 3 3 of Fig. 1, showing a portion of the upper part of the sounding-box and some of the fret-bars and catches or locks to 60 hold the same in contact with the strings. Fig. 4 is an enlarged sectional view, partly in elevation, taken on line 4 4 of Fig. 1, showing a series of press-buttons and levers to operate the dampers. Fig. 5 is a perspective 65 view, partly in section, of one of the fret-bars detached from the frame. Fig. 6 is a fragmental view of a portion of the sounding-box, showing a modification in the manner of arranging the strings in order to produce chords; 70 and Fig. 7 is a sectional view of the upper part of the sounding-box and a portion of one of the side rails, illustrating a modification in the construction of the fret-bars.

In the drawings, 8 represents a sounding- 75 box which may be made of any suitable material and of any suitable construction, but preferably of the form shown in Fig. 1 of the drawings. On the upper surface of this box and at the tail end thereof is secured a bridge 80 9, and at its other end or head is a bridge 10, extending across and resting upon which are a series of strings, (indicated by numerals 11 to 26, inclusive,) but the number of strings may be more or less, if desired. These strings 85 are fastened at one of their ends to the tail of the sounding-box by means of suitable pins 27 and at their other ends to the head of the instrument by means of tuning pins or pegs 28.

Extending parallel with one another on the 90 upper surface of the sounding-box and near its edges of the head portion are located side rails 29, each of which is provided with a series of vertical slots or guideways 30 for the reception and operation of the fret-bars, which 95 are indicated by the numerals 31 to 42, inclusive, but may be more or less in number, and each is provided in its lower portion with a metallic strip 43, and a strip 44, of felt or other soft material, the felt strip extending 100 somewhat farther from the fret-bar than the metallic strip, as is clearly shown in Figs. 2, 3, and 5 of the drawings, will touch and act on the strings, so as to stop the vibration after

the string has been picked, and will also steady or firmly hold the string in place, so that it will not jingle or rattle on the metallic strip, or, in other words, will perform the same function as placing the finger on the string before the fret, as in playing a guitar or cithern. It will be understood that by pressing the fret-bar downward the string or strings will be embedded in the yielding felt until the metal strip constituting a fret, which is placed before the felt, contacts with the strings and produces a clear tone like that produced by a guitar or cithern.

Located in each of the slots 30 of the side rails is a spring 45, on which the ends of the fret-bars rest and are normally held in a raised position, so that the strips 43 and 44 will be out of contact with the strings. On the upper surface of each of the fret-bars and at its middle is located a button or knob 46, to which the thumb or finger may be applied to afford uniform pressure throughout the length of the strips on the strings. Pivoted at one of their ends to the side rails are catches or locks 47, each of which is provided with a knob 48, used for turning them, so as to press and hold the fret-bars in contact with the strings, as is shown in Fig. 3. These catches are located in pairs between two of the fret-bars, so that they may be turned in either direction to secure the bar on either side thereof in a lowered position, and I may use any number of said catches, as is apparent.

Extending from one of the side rails 29 to the other (usually below the strings) and movably secured in their ends adjacent to the tail of the sounding-box are rods 49, 50, and 51, each of which is provided with dampers 52, made of felt or other suitable material and located at proper points between the strings. Each of these rods is provided with a spring 53 to retract it and hold the dampers in contact with the strings. Movably secured on one of the rails 29 in an upright position is a series of rods 54, 55, 56, and 57, each of which is provided at its upper end with a press-button or knob 58 and are pivotally connected at their lower ends to one of the arms of the bell-crank levers 59, fulcrumed on the side rail, to the other arms of which levers are pivotally secured connecting-rods 60, whose other ends are pivotally connected to one of the arms of a series of bell-crank levers 61, horizontally fulcrumed on the side rail, whose other arms are pivotally connected to the rods 49, 50, and 51, thus affording means for shifting said rods longitudinally and throwing the dampers thereon into and out of contact with the strings, as desired.

It will be observed by reference to Fig. 4 that the bell-crank lever on the vertical rod 57 is connected to the rod 60, which unites the lever on the vertical rod 54, thus enabling the rod 51 to be operated by pressing on either of the buttons on said vertical rods and so arranging the buttons that the rods 54 and 55 or 56 and 57 may be pressed down at the

same time by placing the thumb or finger between the two so as to rest on each.

In Fig. 6 I have shown a modification in the manner of arranging the strings, so that the chords may be played by pressing down one fret-bar only or by leaving all strings open, which consists in arranging the strings in groups of four or in chords, as shown. In this modification the dampers may be omitted, but the fret-bars are used, as above stated.

In Fig. 7 is shown a modification in the construction of the fret-bars, which consists in locating a metallic or strip 43½ of other hard substance beneath the bar and strings on the top of the sounding-box and providing the bar with a strip 44 of felt or other material, as before, so that the strings may be pressed down on the strip 43½, thus accomplishing the same result as by the first-named construction. This modification may be used with or without the dampers, as is obvious.

The operation of my instrument is as follows: For example, in playing the C chord with the strings arranged in chord groups of the major triad, as in Fig. 1, all of the fret-bars are left in their raised position and the thumb is run over all the strings. To produce C♯ chord, the fret-bar 31 should be pressed on the strings and the thumb run overall the strings. To produce D chord, bar 32 should be pressed down and all of the strings struck as before. To produce D♯ chord, press down bar 33 and strike all of the strings as before. To produce E, press down bar 34 and strike all of the strings. To produce F chord, press down bar 35 and strike all the strings. To produce F♯, press down bar 36 and strike all the strings. To produce G, press down bar 37 and strike all of the strings. For G♯ press down bar 38 and strike all the strings. For A press down bar 39 and strike all the strings. For A♯ press down bar 40 and strike all the strings. For B press down bar 41 and strike all the strings. For C press down bar 42 and strike all the strings, which will produce C one octave higher than with all strings open. In producing any of the above-named chords the thumb is run continuously overall the strings. In changing any of those chords to minor chords it is necessary to press on the button on the vertical rod 55, which will shift the dampers 52 from strings 21 and 15, or strings V, D♯, to strings 20 and 14, or V, E, as indicated by the tuning-chart 62, used for reference in playing music, and which may be located at a suitable point on the instrument and the letters of which are arranged and inclined as follows:

CEG C C D E G A C C D E G A

to distinguish the octaves. This chart may also be used by which to tune the instrument. To change any of the first-named or major chords to dominant seventh, the buttons on the vertical rods 54 or 57 should be pressed

down, which operation will shift the dampers 52 from strings 12 and 18, or *A**, *A*, thus leaving them undamped. To change any 5 of the major chords to a diminished seventh chord, press down the buttons on the vertical rods 56 and 57, which will shift the dampers 52 from the strings 22 and 16, or *C*, *C**, to 17 and 23, or *C*, *C*, from strings 12 and 18, or *A**, *A*, leaving the latter undamped. To 10 produce dominant to the minor chord, press down buttons on rods 54 and 55, which will shift the dampers from strings 21, 15, 19, and 12, or *D*, *D**, *G*, *A**, and onto strings 20 and 14, or *E*, *E*, only. Each and every one 15 of the shifting dampers will coöperate with each and every one of the fret-bars or chords.

The scale is played in the following manner: C major, for example, is produced by first picking *C*, or 17, string of the middle octave with all the fret-bars up. Then press bar 37 and pick *G* below *C*, which produces D. Then pick *E* above *C* with all fret-bars up. Then press bar 35 and pick *C*, or 17, string, which produces F. Then pick *G* above 25 *C* with all the fret-bars up. Then press bar 35 and pick *E* above *C*, which produces A. Then press bar 37 and pick *E* above *C*, which produces B. Then pick *D* with all bars up, which produces the diatonic scale of C major. 30 All other keys are obtained in the same manner, but by using different fret-bars. The chromatic scale is obtained by picking the above-named strings and by employing the fret-bars 34, 36, and 38 in connection with 35 bars 35 and 37, but are pressed down separately.

In playing pieces the melody is picked with the forefinger, while the accompaniments are obtained by using the thumb—*i. e.*, the music of "Nearer, My God, to Thee" may be 40 written as follows:

45 and to play the same pick the string *E* with all fret-bars up, which is indicated by 0. Then pick *G* and press bar 37, then *C* with bars up, then *G* and press bar 35, then *E* and press bar 35, then *E* and press bar 35, then 50 *G* with all bars up, then *C* with all bars up, then *E* with all bars up, then *C* and press bar 37. Where the letters have dots, as *G* and *C*, the strings are picked, and where no dots are used the strings are played in chords to 55 the string indicated. The chords are played when the strings are arranged in groups, as shown in Fig. 6, by picking tonic first, then subdominant, then dominant seventh, and if minor is wanted then the minor group may 60 be picked in a like manner, the chart 63 being used to distinguish the tonic, subdominant, dominant seventh, and minor chords and may also be used for tuning. These groups are designated on the drawings by the 65 words "Minor" to indicate the minor group, "Tonic" for the tonic or first chord of the key, "Sub-dom." for the subdominant or sec-

ond chord of the key, and "Dom. seventh" for dominant seventh or third chord of the key. As the bars are placed a half-tone 70 apart, it will be noted that by pressing down bar 31 on the groups of strings the key will be changed a half-tone higher and by pressing down bar 32 it will be changed another half-tone higher, and so on in this manner all the 75 keys are obtained throughout the twelve bars.

Having thus fully described my invention, what I claim as new, and desire to secure by Letters Patent, is—

1. In a musical instrument, the combination with a sounding box or body, of a series of strings thereon, a series of metal strips extending crosswise the body and a series of felt strips also extending crosswise the body, said metal strips and felt strips being arranged to operate in conjunction with one another on the strings, the felt strips serving to stop the vibration of the strings and the metal strips to produce a clear tone. 80

2. In a musical instrument, the combination of a sounding box or body, of a series of strings thereon, a series of metal strips extending crosswise the body, and a series of felt strips also extending crosswise the body, said metal strips and felt strips being arranged to operate in pairs, and in conjunction with one another on the strings, the felt strips serving to stop the vibration of the strings and the metal strips to produce a clear tone. 95

3. The combination with a sounding box or body, of a series of strings thereon, a series of spring-actuated and vertically-movable bars, each provided with a strip of felt or like material, and a strip of metal or other hard material extending crosswise the body, said strips 100 adapted to be brought in contact with the strings.

4. In a musical instrument, the combination of a sounding box or body, of a series of strings thereon, a series of spring-actuated 110 and vertically-movable bars, each provided with a strip of felt or like material, and a strip of metal or other hard material in its lower part extending crosswise the body, a number of movable rods each provided with 115 dampers and extending crosswise the body and means to shift the dampers.

5. The combination with a sounding box or body, of a series of strings thereon, parallel side rails on the upper surface of the body, 120 said rails having vertical guideways or slots, springs located in said guideways, bars resting at their ends on said springs, and each provided in its lower part with a strip of felt or like material, and a strip of metal or other 125 hard substance, a number of catches pivotally connected to the side rails between the bars, and adapted to hold the same in a lowered position, substantially as described.

6. In a musical instrument, the combination of a sounding box or body, of a series of strings thereon, two parallel side rails on the upper surface of the body on each side of the strings, said rails having vertical slots or

- guideways, springs located in said slots, bars extending across the strings and resting their ends on said springs, each of said bars being provided in its lower surface with a strip of felt or similar material, and a strip of metal or other hard substance, a number of catches pivotally secured on the side rails between the bars and adapted to engage the bars and hold them in a lowered position, a number of 5 movable and spring-actuated rods extending crosswise the strings, each having dampers, and a mechanism to shift said dampers, substantially as described.
- 10 7. The combination of a sounding box or

body, with a series of strings thereon, the 15 movable and spring-actuated rods 49, 50 and 51, each having dampers 52, the rods 54, 55, 56, and 57, vertically supported above the sounding-body, the levers 59 and 61, and the connecting-rods 60, uniting the vertical rods 20 and first-named rods, the vertical rods 54 and 57 being connected so as to move in unison, substantially as described.
